UNITED STATES PATENT OFFICE.

JOHN DOLAN, OF HASTINGS, NEBRASKA.

RAIL-FASTENING.

1,358,832.

Specification of Letters Patent. Patented Nov. 16, 1920.

Application filed May 27, 1920. Serial No. 384,625.

To all whom it may concern:

Be it known that I, JOHN DOLAN, a citizen of the United States, residing at Hastings, in the county of Adams and State of Nebraska, have invented certain new and useful Improvements in Rail-Fastenings, of which the following is a specification.

This invention relates to an improved track rail fastening and has one of its 10 principal objects to provide a device of this character whereby the rails of a railway track may, without the necessity for any special structural features in the track ties or the use of ordinary spikes, be readily 15 secured to the ties.

A further object of the invention is to provide a device which will be particularly adapted for use in connection with cement ties but which may also be readily employed 20 in connection with wooden ties.

And the invention has as a still further object to provide a device which will securely and firmly engage a track rail and wherein adjustment will be provided whereby the 25 rail may be firmly clamped in position.

Other and incidental objects will appear hereinafter.

In the drawings:

Figure 1 is a fragmentary plan view 30 showing a pair of my improved devices in connection with a track rail and ties of ordinary construction,

Fig. 2 is a vertical section through the device, the rail being shown in elevation,

Fig. 3 is a transverse section through the device, and

Fig. 4 is a perspective view showing the cushioning block employed.

In order to facilitate an accurate understanding of the present invention, I shall describe the device in connection with a tie 10 and rail 11 of conventional design. In carrying the invention into effect, I employ a top tie plate 12 which is seated against 15 the upper face of the tie to extend transversely thereof and arranged beneath the tie is a similar tie plate 13, these plates overhanging the tie at its side edges. Rested upon the top plate are companion clamping 20 plates 14 formed to snugly fit around the base flange of the rail extending there beneath to closely confront each other. As will be observed upon reference to Fig. 1, the clamping plates are of a length substantially 25 equal to the length of the plates 12 and 13 while the top flanges 15 of said plates termi-

nate short of the ends thereof. Seated upon the bottom flanges of the clamping plates beneath the rail is a cushioning block 16. This block may be of wood or other approved material and is designed to yieldably support the rail so that the major portion of the stress set up by the passage of rolling stock over the rail will be absorbed by the block and thus interrupted between the rail 60 and tie. Engaged through the bottom flanges of the clamping plates at the respective ends thereof are pairs of clamping bolts 17 which extend through the top and bottom plates 12 and 13 at opposite sides of 65 the tie. Said flanges and the plates are provided with slots freely receiving the bolts so that the bolts may be readily adjusted to compensate for ties of different widths and, as will be at once appreciated, said bolts will 70 serve to clamp all the plates firmly upon the tie so that the clamping plates 14 will be anchored for rigidly holding the rail. Further, the bolts will coat with the opposite sides of the tie for preventing shifting of 75 the plates transversely of the tie while the nuts at the upper ends of the bolts will confront the end edges of the cushioning block 16 for preventing longitudinal shifting of 80 said block. An especially secure and rigid 85 fastening for the rail is thus provided while, at the same time, the use of the ordinary rail spikes is eliminated. Consequently, the present device will prove particularly desirable for use in connection with cement 90 ties, it being observed that no special structural features will be required in the tie in order that the device may be used thereon. However, as will also be appreciated, the device may be readily employed in connection 95 with wooden ties. By inserting the clamping bolts 17 first through the bottom plate 13 and then through the top plate 12, the bolts may be assembled upon the bottom plate and this plate laid beneath the tie at 100 the time the tie is laid in place, when the top plate 12, clamping plates 14 and cushioning block 16 may then be assembled beneath the track rail upon the top of the tie at the time the rail is laid. This done, it 105 is simply necessary to apply the nuts to the clamping bolts and properly adjust said nuts for binding the device in engagement with the tie and binding the rail thereto, it being also, of course, possible by adjustment 110 of said nuts, to take up any looseness which may later occur.

Having thus described the invention, what is claimed as new is:

1. A rail fastening including top and bottom tie plates, rail clamping plates seated upon the top tie plate, a rail cushioning block extending within the rail clamping plates, and clamping means connecting all of said plates, said means confronting the ends of the cushioning block for holding the block against longitudinal displacement.
- 5 2. A rail fastening including top and bottom tie plates, clamping plates formed to fit the base flange of a rail and extending therebeneath, said clamping plates being seated upon the top tie plate, and clamping means connecting all of said plates.
- 10 3. A rail fastener including top and bot-

tom tie plates, rail clamping plates sustained by the top tie plate, and clamping means securing said plates and adjustable laterally 20 with respect to each other.

4. A rail fastener including top and bottom tie plates provided with elongated openings, rail clamping plates sustained by the top tie plate and provided with elongated 25 openings registering with the openings at the top tie plate, and clamping means extending through said openings and connecting all of said plates, said clamping means being adjustable laterally with respect to 30 each other within the openings.

In testimony whereof I affix my signature.

JOHN DOLAN. [L. S.]
